UNITED STATES PATENT OFFICE.

JOHN R. NAGY, OF MARTINS FERRY, OHIO.

RAIL-JOINT.

1,098,829.

Specification of Letters Patent.

Patented June 2, 1914.

Application filed August 20, 1913. Serial No. 785,665.

To all whom it may concern:

Be it known that I, JOHN R. NAGY, a citizen of the United States of America, residing at Martins Ferry, in the county of Belmont and State of Ohio, have invented certain new and useful Improvements in Rail-Joints, of which the following is a specification, reference being had therein to the accompanying drawing.

10 This invention relates to rail joints, and the primary object of my invention is to provide a rail joint that can be advantageously used in connection with that type of metallic tie and rail fastener disclosed in my 15 companion application filed under even date.

A further object of this invention is to provide a rail joint embodying splice bars one of which is constructed to interlock with a rail head carried by the other splice bar.

20 A still further object of this invention is to provide a simple, durable and inexpensive rail joint that can be easily and quickly installed without resorting to the use of skilled labor or bolts and nuts.

25 With the above and other objects in view the invention resides in the novel construction, combination and arrangement of parts to be hereinafter specifically described and then claimed.

30 Reference will now be had to the drawing, wherein:—

Figure 1 is a plan of the rail joint, Fig. 2 is a cross sectional view of the same, Fig. 3 is a perspective view of a portion of one of the splice bars, Fig. 4 is a similar view of another splice bar, Fig. 5 is a plan of a portion of a tie, and Fig. 6 is a side elevation of the same.

In the drawing the reference numeral 1 40 denotes rails having base flanges 2 and bracing the sides of said rails are splice bars 3 and 4. The splice bar 3, intermediate the ends thereof has a web 5 and a rail head 6,

said rail head having the free edge thereof provided with a depending lip 7. The splice 45 bar 4, intermediate the ends thereof, has an offset portion 8 and a cut away portion 9, the cut away portion 9 providing clearance for the lip 7 whereby the offset portion 8 can fit up under the rail head 6. The splice bars 3 50 and 4 are adapted to be held against the rails 1 by inner rail fasteners 10, outer rail fasteners 11 and auxiliary outer fasteners 12. The fasteners 10 and 11 are formed integral with a metallic slab 13 and this slab together 55 with the fasteners thereof forms the subject matter of my companion application.

What I claim is:—

1. In a rail joint, rails, splice bars bracing the sides of said rails, a rail head formed integral with one of said splice bars and interposed between said rails, a depending lip carried by said rail head, an offset portion carried by the other of said splice bars and adapted to engage under said head, and the 65 last mentioned splice bar being cut away to provide clearance for said lip.

2. In a rail joint, rails, splice bars bracing the sides of said rails, a rail head formed integral with one of said splice bars and interposed between said rails, a depending lip carried by said rail head, an offset portion carried by the other of said splice bars and adapted to engage under said head, the last mentioned splice bar being cut away to provide 75 clearance for said lip, and means including fasteners adapted to engage the edges of said splice bars and retaining said splice bars in engagement with said rails.

In testimony whereof I affix my signature 80 in the presence of two witnesses.

JOHN R. NAGY.

Witnesses:

W. M. B. DULAY,
S. J. SHANE.
